PORTABLE SCREEN HOUSE

Filed Aug. 28, 1928

INVENTOR:

GUSTAV A. BAUMANN,

By: Otto H. Kinsler,

hisatty.

UNITED STATES PATENT OFFICE

GUSTAV A. BAUMANN, OF LOS ANGELES, CALIFORNIA

PORTABLE SCREEN HOUSE

Application filed August 28, 1928. Serial No. 302,468.

This invention relates to structures in which a bed or similar resting support is arranged within a screened-off housing.

One of the objects of this invention is to provide a screen housing for an individual resting bed or resting place.

Another object is to provide a mounting structure by which the housing is swingably supported.

10 Another object is to provide means on the supporting structure whereby the whole structure with the screen housing is made portable.

Another object is to provide means by 15 which the housing is swingably suspended from the supporting structure.

Another object is to provide locking means whereby the swingable housing can be held in stationary position when suspended in the 20 frame structure.

Another object is to provide slanting sides in the housing including hanging doors mounted in such a way that the doors can be opened at the bottom when not locked, so that 25 a person may enter and leave the housing without material effort in handling the doors.

Another object is to provide inside and outside locking means for the hanging doors.

Other objects will appear from the following description and appended claim as well 30 as from the accompanying drawing, in which—

Fig. 1 is a front elevation of a portable frame structure with a screen housing suspended from this frame structure, the front door being removed to show a bed inside of the housing according to this invention.

Fig. 2 is an end elevation of the housing 40 with one end of the frame structure cut away on lines 2—2 of Fig. 1.

One of the principal features of this invention is to provide a screen house of portable form that may be used in a private home 45 as well as in a sanatorium, having in mind that in a sanatorium patients have to be moved around a great deal for the comfort of the patients as well as to give the patients proper air and proper shade, or eventually 50 sun during all of the day to follow the changes

under which the advantage of the sunlight may be had.

As illustrated in the drawing, the house 3 is provided with a roof 4 mounted on top of upright end walls 5 and comparatively slanting side walls 6 and 7. All the walls are provided with a screen to admit air and sunlight from any direction.

Swinging sashes 8 are suspended on the upper edge on hinges or other similar suitable pivot connection as indicated at 9 whereby the door hanging perpendicular provides a suitable opening in the lower part through which a person may pass in and out without material effort otherwise necessary to move a door.

Locks or sliding bolts 10 and 11 are provided on the outside and inside whereby the suspended doors may be locked from the outside and from the inside.

The whole house 3 is suspended by chains 12 over a cross bar 13 in the upper end 14 of the end structures 15. The oppositely disposed end structures are interconnected at the bottom as indicated at 16 and are provided 75 on the underside with castors 17 whereby the whole structure with the housing can be moved about to make this screen housing structure portable.

By the chains 12 the screen housing can 80 swing back and forth between the uprights 15 so that a patient may be swung or may swing himself with very little effort.

To arrest the swinging movements a pawl 18 is pivotally connected to the end walls 5 of the housing, as indicated at 19. The pawl 18 is bifurcated to engage over the sides of the inner bracing 20 of the end structures 15 to lock the housing in stationary position within the frame structure.

A holding hook 21 is provided on each of the end walls 5 whereby the pawl 18 can be held against the end walls 5 of the housing when the housing is desired to swing freely between the end uprights of the frame structure.

A bed 22 is roughly outlined inside of the screen house, but it must be understood that any other suitable support, as a chair, can be placed in such a housing.

Having thus described my invention, I claim:

A portable screen house embodying a frame structure consisting of a base including castors on its underside by which the frame structure can be moved about and uprights having a cross bar disposed near the upper terminations across the structure, a housing proper suspended from said cross bar by flexible means, the housing having slanting sides, sashes hingedly connected along the upper edges to the slanting sides of the housing so that the sashes allow a passing into and out of the housing when the sashes hang in a perpendicular manner on the hinges on the slanting sides of the housing, the sashes as well as the other sides of the housing being screened-in to admit air and light from all sides, resting accommodations disposed in the housing, 10 pawls pivotally mounted on the opposite end-sides of the housing and having bifurcated ends adapted to engage with certain parts of the frame structure whereby the housing can be held against swinging movements within the frame structure, locking means on the inside and outside of the sashes whereby the sashes can be held locked within the slanting sides of the housing, and a catch to hold the pawls 20 in disengaged position and adapted to free the housing for swinging movements within the frame structure.

In testimony that I claim the foregoing as my invention I have signed my name.

GUSTAV A. BAUMANN.
